UNITED STATES PATENT OFFICE.

CHARLES P. MOSHER, OF PHILADELPHIA, PENNSYLVANIA, ASSIGNOR TO
THE ENTERPRISE MANUFACTURING COMPANY OF PENNSYLVANIA,
OF SAME PLACE.

DESIGN FOR A SAD-IRON HANDLE.

SPECIFICATION forming part of Design No. 33,660, dated December 4, 1900.

Application filed November 10, 1900. Serial No. 36,128. Term of patent 14 years.

To all whom it may concern:

Be it known that I, CHARLES P. MOSHER, a citizen of the United States, residing in Philadelphia, Pennsylvania, have invented and produced a certain new and original Design for a Sad-Iron Handle, of which the following is a specification.

My design for a sad-iron handle is clearly illustrated in the accompanying drawings, in which—

Figure 1 is a perspective view illustrating the handle. Fig. 2 is a plan view, and Fig. 3 is an end view.

The essential feature of the design is the handle having ornamental side extensions, as illustrated.

F is the base of the handle.

F' is the handhold.

Projecting from each side of the base are ornamental side extensions F², consisting of arms f f, projecting laterally from each end of the iron and connected to a bar f', as shown.

I claim—

The design for a sad-iron handle as herein described and as illustrated in the accompanying drawings.

In testimony whereof I have signed my name to this specification in the presence of two subscribing witnesses.

CHARLES P. MOSHER.
